COMBINED REFLECTOR AND SOCKET COVER FOR PORTABLE LAMPS

Henry Dreyfuss, South Pasadena, Calif., assignor to Rex Cole, Inc., New York, N. Y., a corporation of New York

Application May 15, 1956, Serial No. 41,505

Term of patent 14 years

(Cl. D48—16)

T1Q-1.

Figure 1 is a side elevational view of the combined reflector and socket cover for portable lamps, showing my new design; and

Figure 2 is a top plan view of the same.

I claim:

The ornamental design for a combined reflector and socket cover for portable lamps, as shown.
